UNITED STATES PATENT OFFICE

FERRY M. FORBES, OF DETROIT, MICHIGAN, ASSIGNOR TO PREMIER CUSHION SPRING COMPANY, OF DETROIT, MICHIGAN, A CORPORATION OF MICHIGAN

HELICAL COILER AND ASSEMBLER

Application filed August 15, 1927. Serial No. 213,051.

The present invention pertains to a novel machine for intersecting helical springs of the type used for joining the conical springs of spring cushion constructions. Hitherto these intersected springs or ties have been wound one into the other by hand. The object of the present invention, as already indicated, is to provide a machine for this operation.

10 The machine of the invention includes a holder into which the helical spring issuing from the forming element is received. By means of suitable timed mechanism, the formed spring is gripped in the holder, 15 severed from the original wire, and the holder is then turned to a position which brings the formed spring into a line intersecting the line of ejection from the forming element. While the formed spring is held in 20 such position, another spring section is coiled in the forming element and ejected therefrom so that it passes through the first formed spring. After the formation of the second spring, the cutter again comes into 25 operation, and an ejector discharges the two intersected springs from the holder. This cycle is repeated, whereby the intersected springs or ties are formed in an automatic and continuous operation.

30 The invention is fully disclosed, by way of example, in the following description, and in the accompanying drawings, in which—

Figure 1 is an end view of the machine;

Fig. 2 is a plan view thereof;

35 Fig. 3 is a detail of Figure 2, showing the ejector rod advanced one stage;

Fig. 4 is a side elevation partly broken away to show the inner cam structure;

40 Fig. 5 is a section on the line 5—5 of Figure 4;

Fig. 6 is a detail plan view, showing the coil holder in a tilted position;

Fig. 7 is a fragmentary vertical section showing the front end of the coil holder in 45 elevation; and

Fig. 8 is a similar section showing the coil holder in tilted position and a second coil passed through the first coil.

Reference to these views will now be made 50 by use of like characters which are employed

to designate corresponding parts throughout.

The machine has a frame which includes a base 1 and a pair of side walls 2 and 3 in which is journaled a main shaft 4 equipped at one end with a pulley 5. The shaft 4 carries a gear 6 to which is affixed a face cam 7 and a cylindrical cam 8. The functions of these cams are described in greater detail hereinafter.

A pair of brackets 9 extend inwardly from the wall 3 and have a rocker 10 pivoted therebetween. One end of the rocker carries a roller 11 riding on the cam 8 and held in place by a headed pin 12 secured in the same end of the rocker. The wall 3 is also provided at its upper edge with a pair of spaced upright fingers 13 between which is inserted a sleeve 14 lying substantially parallel to the shaft 4. The sleeve is formed with guideways 15 which receive the fingers 13 as shown in Figures 1, 2 and 6. The members 9 and 14 are formed at diametrically opposite points with aligned ears 16 and 17 respectively through which are passed bolts 18. The lower end of each bolt has a rounded head 19 bearing on the lower surface of the adjacent ear 16, and the upper end is clamped to the corresponding ear 17 by nuts 20. The sleeve 14 is penetrated by a rotatable countershaft 21 having at one end a pinion 22 meshing with the drive gear 6 and at the other end a grooved feed roller 23.

45 A spring 24 (Figures 1 and 4) inserted between the fingers 13 and bearing upwardly on the sleeve 14 tends to lift the roller 23. Another feed roller 25 positioned directly beneath the roller 23 is carried loosely by the main shaft 4 and is rotated only when in tangential contact with the member 23. In line with the common tangent to the rollers, the frame carries a pair of bearings 26 in which are secured aligned guides 27 at opposite sides of the tangential point of contact 95 for the purpose of maintaining the wire 28 which is received in the grooves of the rollers and fed into the machine by the rollers when in contact.

50 The deflector or coiler of the machine 100

comprises, as usual, a block 30 bolted to the frame at 31 and having a groove 32 of such configuration as to coil the wire 28 as it is passed therethrough. The helical spring 33 formed in this manner is ejected at substantially right angles to the entering straight wire 28. The pitch of the spring is determined by a wedge shaped spacer 34 lying adjacent the coiler 30 and 10 formed on the end of a bar 35 having opposed converging sides 36, one of which engages the base of a correspondingly formed notch 37 cut in the outer face of the wall 3 and the other of which is engaged by a clamp 38 bolted on the top of this wall. The pitch of the spring may be altered by adjusting the bar 35 longitudinally in the notch 37.

A bearing 40 is formed along the upper 20 edge of the wall 3 and has a sleeve 41 rotatably mounted therein as clearly shown in Figure 3. In the sleeve is slidably mounted an ejector or kick-out rod 42. The forward or inner end of the rod 41 has fixed thereto, exteriorly of the bearing 40, a head 43 having a pair of spaced fingers 44 projecting therefrom at one side of the axis of the rod. In the head 43 are pivoted a pair of gripping fingers 45 positioned to cooperate with the fingers 44. The concealed end 46 of each pivoted finger is engaged by a compressed spring 47 inserted in the head whereby the fingers 45 are normally urged towards the fingers 44. The lower edges 25 of the pivoted fingers are notched or undercut as at 48, and the inner end of the rod 42 carries a head 49 which, when partially retracted from the notches as shown in Figure 4, holds the pivoted fingers 45 loose 30 with respect to the coil spring, and which when received entirely in the notches, permits the pivoted fingers to clamp the coil against the fixed fingers 44 and head 49.

A cutter bar 50 is slidably mounted transversely of the frame and carries at one end a cutting tool 51, the cutting edge of which is adapted to pass across the groove 32 in the deflector 30. When actuated for the purpose of cutting, the cutting edge of the 35 tool cooperates with one of the lower edges of the spaces 34 to effect shearing of the wire.

The cam 8 has a depression 8' (Figure 4) which, when entered by the roller 11 on 40 the rocker 10, permits the other end to rise, followed by a lifting of the roller 23 under the action of the spring 24. At this time the rollers 23 and 25 are relaxed with reference to the wire 28; and the feeding of 45 the wire to the coiler is discontinued. The higher part of the cam 8 is so dimensioned that it will feed sufficient wire for the desired length of coil before the roller 23 is lifted.

50 Another countershaft 55 is journaled in

the machine parallel to the shafts 4 and 21 and carries a gear 56 meshing with a pinion 57 of half size on the shaft 4. Consequently the shaft 55 is driven at half the angular velocity of the shaft 4. On the shaft 55 is mounted a face cam which has a rise 58 and a depression 59 joined by slopes 60. The back of this cam has a shoulder 61 surrounded by an edge cam 62 fixed to the gear by screws 63 passed through slots 64 in the cam. The member 62 fits over the shoulder 61 and thus constitutes a clamp, in conjunction with the screws 63, whereby both cams are bound to the gear 56 which is keyed to the shaft 55. At one end of the machine is formed a bracket 64 which, with an upright bearing 65 on the base of the machine, supports a shaft 66 also parallel to the shaft 4. One end of the shaft has secured thereto an arm 67 carrying at its free end a roller 68 which rides on the cam 62 as shown in Figure 4. The ejector rod 42 carries at its outer end a sleeve 69 in which the rod may turn but does not slide. Ears 70 extend laterally from the sleeve 69 and receive the fingers 72 of a forked arm 71 secured to the shaft 66. When the roller 23 is lifted by the action already described, the roller 68 drops into a depression 73 in the cam 62 of such size as to slide the rod 42 until the spacing head 49 at the forward end thereof enters the notches 48 in the pivoted fingers 45 so that the latter are spring pressed upon the coil 33 therebelow. As soon as the helical spring is thus gripped, the cam 7 passes a roller 74 carried by the cutter bar 50 whereby the latter is shifted to shear the wire and separate the coil 33. The roller 74 is held firmly in engagement with the cam 7 and the bar 50 is normally retracted by a spring 50' surrounding the outer end thereof and compressed between the side wall 2 and a washer 50'' carried by the bar as shown in Figure 1.

At the base of the machine is still another bearing 75 accommodating a shaft 76 having an arm 77 at the inner end thereof and a longer arm 78 at the outer end. This arm is joined by a link 78' to still another arm 79 fixed to the sleeve 41. The shorter arm 77 carries a roller 80 which rides on the cam 58—60. The arm 77 has an extension 81 (Figure 1) connected to the frame by a spring 81' which holds the roller 80 firmly in contact with the cam 58—60. Immediately after the wire has been cut, and while the roller 68 is still in the depression 73, the roller 80 passes from the rise 58 to the depression 59 of the cam and thus causes the sleeve 41 to be moved through 90° from the position shown in Figure 7 to that shown in Figure 8. It will be seen from Figure 4 that after this action the rollers 68 and 80 are not displaced by their respective cams

for about 180°. During this period however the contact between the feed roll 23 and 25 has been resumed and another length of wire is passed through the coiler. The front of the head 49 carries a guide 49' which receives this second coil and permits it to be wound through the first coil as shown in Figure 8. Figures 2 and 3 show that one of the pivoted fingers 45 extends forwardly farther than the other so that the first coil is ejected from the coiler in a line not exactly parallel to the transverse axis of the machine.

Before another displacement of the cams 68 and 80 occurs, the cutter is again actuated since its operating cam 7 travels at twice the angular velocity of the cams on the shaft 55. After the second coil has been cut, the roller 68 drops into a still deeper depression 82 in the cam 62, and this movement causes the ejector rod to be thrust forward from the position shown in Figure 3, whereupon the intersected helical springs are moved from beneath the fingers 45 against the action of the springs 47 and thus ejected from the machine. The forward face 49" of the head 49 has the same angularity as the axis of the first formed coil 33. The roller 68 is then returned to the high part of the cam 62 so that the spacing head 49 is retracted to open the holder, and at the same time the roller 80 is returned to the rise 58 whereby the holder is moved to its original position for receiving a new coil beneath the spring fingers 45. The cycle already described is repeated. The timing may be adjusted by loosening the screws 63 and shifting the cams on the shaft 55 with respect to the gear 56.

Although a specific embodiment of the invention has been illustrated and described, it will be understood that various alterations in the details of construction may be made without departing from the scope of the invention as indicated by the appended claims.

What I claim is:

1. A spring forming machine comprising a helical spring forming and ejecting element and means for feeding wire thereto, the combination of a holder adapted to receive the spring issued from said element, means for tilting said holder to retain the spring in a line intersected by the line of ejection from said element, means for maintaining said holder in tilted position during the formation of another spring and an ejector operable in said holder and adapted to eject said spring into the first spring while held in said position.

2. A spring forming machine comprising a helical spring forming and ejecting element and means for feeding wire thereto, the combination of a holder comprising fixed and spring pressed fingers adapted to grip the spring issued from said forming element,

a spacer block adapted to hold said spring pressed fingers spaced from the spring, and means for pushing said block to the free ends of said fingers whereby to eject the spring from the holder.

3. A spring forming machine comprising a helical spring forming and ejecting element and means for feeding wire thereto, the combination of a holder comprising fixed and spring pressed fingers adapted to grip the spring issued from said forming element, a spacer block adapted to hold said spring pressed fingers spaced from the spring, means for tilting said holder to retain the spring in a line intersected by the line of ejection from said forming element, and means for pushing said block to the free ends of said fingers whereby to eject the spring from the holder.

4. A spring forming machine comprising a helical spring forming and ejecting element and means for feeding wire thereto, the combination of a holder comprising fixed and spring pressed fingers adapted to grip the spring issued from said forming element, a spacer block adapted to hold said spring pressed fingers spaced from the spring, and means for pushing said block to the free ends of said fingers whereby to eject the spring from the holder, said spring pressed fingers being notched to receive the block whereby to permit said fingers to clamp the spring.

5. A spring forming machine comprising a helical spring forming and ejecting element and means for feeding wire thereto, the combination of a holder comprising fixed and spring pressed fingers adapted to grip the spring issued from said forming element, a spacer block adapted to hold said spring pressed fingers spaced from the spring, means for tilting said holder to retain the spring in a line intersected by the line of ejection from said forming element, and means for pushing said block to the free ends of said fingers whereby to eject the spring from the holder, said spring pressed fingers being notched to receive the block whereby to permit said fingers to clamp the spring.

6. A spring forming machine comprising a helical spring forming and ejecting element and means for feeding wire thereto, the combination of means for tilting the formed spring to a line intersected by the line of ejection from said element, a severing device adjacent said forming element, and means for stopping said feeding means and actuating said severing device prior to tilting said spring.

7. A spring forming machine comprising a helical spring forming and ejecting element and means for feeding wire thereto, the combination of a holder adapted to receive the spring issued from said element,

means for tilting said holder to retain the spring in a line intersected by the line of ejection from said element, a severing device adjacent said forming element, and means for stopping said feeding means and actuating said severing device prior to tilting said holder.

8. A spring forming machine comprising a helical spring forming and ejecting element and means for feeding wire thereto, the combination of a holder adapted to receive the spring issued from said element, means for tilting said holder to retain the spring in a line intersected by the line of ejection from said element, a severing device adjacent said forming element, means for stopping said feeding means and actuating said severing device prior to tilting said holder, and an ejector operable in said holder.

9. A spring forming machine comprising a helical spring forming and ejecting element and means for feeding wire thereto, the combination of a holder comprising fixed and spring pressed fingers adapted to grip the spring issued from said forming element, a spacer block adapted to hold said spring pressed fingers spaced from the spring, means for tilting said holder to retain the spring in a line intersected by the line of ejection from said forming element, means for pushing said block to the free ends of said fingers whereby to eject the spring from the holder, a severing device adjacent said forming element, and means for stopping said feeding means and actuating said severing device prior to tilting said holder.

10. A spring forming machine comprising a helical spring forming and ejecting element and means for feeding wire thereto, the combination of a holder comprising fixed and spring pressed fingers adapted to grip the spring issued from said forming element, a spacer block adapted to hold said spring pressed fingers spaced from the spring, means for tilting said holder to retain the spring in a line intersected by the line of ejection from said forming element, means for pushing said block to the free ends of said fingers whereby to eject the spring from the holder, said spring pressed fingers being notched to receive the block whereby to permit said fingers to clamp the spring, a severing device adjacent said forming element, and means for stopping said feeding means and actuating said severing device prior to tilting said holder.

11. In testimony whereof I affix my signature.
FERRY M. FORBES.
